(57) **CLAIM**

The ornamental design for an earphone with charging case, as shown and described.

DESCRIPTION

FIG. 1 is a perspective view of an earphone, of the earphone with charging case, showing my new design; the earphone is shown separately for ease of illustration;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of a charging case, of the earphone with charging case, shown separately for ease of illustration;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof;

FIG. 14 is a bottom plan view thereof; and,

FIG. 15 is a perspective view showing the earphone, of the earphone with charging case, received in the charging case. The broken lines depict portions of the earphone with charging case that form no part of the claimed design.

1 Claim, 15 Drawing Sheets
